US00D561840S

(12) **United States Design Patent** (10) Patent No.: **US D561,840 S**
(45) Date of Patent: **** Feb. 12, 2008**

(54) **SIMULATED GAME DEVICE**

(75) Inventor: **Koji Osuka**, Tokyo (JP)

(73) Assignee: **Sega Corporation**, Tokyo (JP)

(**) Term: **14 Years**

(21) Appl. No.: **29/273,102**

(22) Filed: **Feb. 27, 2007**

(30) **Foreign Application Priority Data**

Aug. 28, 2006 (JP) 2006-022701

(51) LOC (8) Cl. **21-01**

(52) U.S. Cl. **D21/325**

(58) **Field of Classification Search** D21/324-327,
D21/333, 811, 369; 273/148 B, 148 R; 463/1,
463/29-35, 46-51, 58

(57) **CLAIM**

The ornamental design for simulated game device, as shown and described.

DESCRIPTION

FIG. 1 is a front elevational view of a simulated game device showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines, which define the bounds of the claimed design, form no part thereof. The broken lines environmental are for illustrative purpose only and form no part of the claimed design.
